UNITED STATES PATENT OFFICE.

FRANK W. ROBINSON, OF READING, PENNSYLVANIA.

SPLICING MECHANISM FOR CIRCULAR-KNITTING MACHINES.

Application filed August 22, 1922. Serial No. 583,538.

To all whom it may concern:

Be it known that I, FRANK W. ROBINSON, a citizen of the United States, residing at Reading, county of Berks, State of Pennsylvania, have invented a new and useful Splicing Mechanism for Circular-Knitting Machines, of which the following is a specification.

My present invention relates particularly to an organization for splicing in a circular knitting machine. The invention has been shown in connection with parts of a circular knitting machine of the Banner type made under Letters Patent of the United States granted to Hemphill #933,443, of 1909, it being of course understood that the invention is not limited in its use to machines of this type.

With the above in view, my invention consists of a novel construction and arrangement of splicing mechanism for circular knitting machines.

It further consists in features, combination and arrangement of parts hereinafter described and particularly pointed out in the claims.

For the purpose of illustrating my invention, I have shown the accompanying drawings a typical embodiment thereof which is at present preferred by me, since this embodiment will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents a side view of the knitting head with my invention applied thereto.

Figure 2 represents a top plan view showing more particularly certain cams employed.

Figure 3 represents, in side elevation, a portion of the machine showing more particularly the knitting wave and certain of the cams in the position which they assume during the knitting operation.

Figure 4 represents, in front elevation, the parts seen in Figure 2 and in a different relation from that seen in Figure 3.

Similar numerals of reference indicate corresponding parts in the figures.

55

Referring to the drawings.

In knitting the high splice or double sole of stockings, the splicing yarn is thrown into work to be knitted together with the main yarn and when thrown into work it is knitted up for a half revolution of the machine. The yarn finger remains in position to place the splicing yarn in the work during the knitting of the high splice and the double sole, and the needles are so controlled that only the proper set or half circle will take the yarn to knit the high splice or double sole, the other needles or half circle missing the splicing yarn so that for only one-half revolution of the machine the splicing yarn is knit. This is done only on the short butt needles which make the high splice and sole of the stocking. The needles are divided in two sets as in the Banner type of machine, one-half circle being insert needles and the other half circle being heel and toe needles, the heel and toe needles having preferably short butts and the insert needles having preferably long butts.

60

My present invention relates more particularly to the cams employed for controlling the needles. These cams include stitch cams 1 and 2, respectively, the stitch cam 2 being fixedly mounted and of the usual construction while the stitch cam 1 is pivotally supported, as at 3, in proximity to its lower end. These two stitch cams are used in reciprocating knitting for heel and toe work and the stitch cam 1 is in use during round knitting.

65

4 designates the top center or guard cam which acts to retract the needles after being advanced to take the yarn. This cam 4 is provided with slots 5 through which pass fastening devices 6 which engage the block 7 which carries the cams. The cam 4 has connected to it an arm 8 which is connected to one end of a bell crank lever 9 pivotally supported at 10 and to the opposite end of this bell crank lever 9 is connected a link 11 to which is secured one end of a lever 12 suitably fulcrumed, said lever being controlled by a cam 13 carried by the shaft on which the main pattern drum of the Banner machine is supported in the Hemphill

patent to which reference has before been made. The link 11 is longitudinally adjustable by means of the socket 14 with which it has threaded engagement, the 5 socket 14 being connected with the lever 12.

The operative cam surface of the cam 4 is of the usual construction. The main yarn finger is shown at 15 and the splicing yarn finger is shown at 16 other yarn 10 fingers being shown at 17. The cam 4 carries a screw 18 which is in frictional engagement with the block 7. The yarn fingers 17 and the narrowing pick mechanism 20 operate in the usual well known manner.

15 When the heel and toe is being formed the cam 4 is all the way in and when the splice thread is in use, the cam 4 is half way in. It is not necessary to employ the screw 18, the only function of this screw being 20 to increase the friction of the cam 4. The stitch cam 1 is pivoted so that on the reverse movement the needles can pass over such stitch cam, which at such time is in its lower position, and pass under the cam

25 4. When the cam 4 is moved rearwardly and the stitch cam 1 is raised, as in Figure 3, the needles are divided, the needles with short butts passing directly across the face of the cam 4 while the needles with the 30 long butts are drawn down by the cam 4 to a lower level. I preferably provide an adjustable set screw 21 to limit the downward movement of the movably mounted stitch cam 1 and the flange 22 limits the 35 extent of its upward movement, see Figure 3.

It will now be apparent that I have devised a new and useful splicing mechanism for circular knitting machines which embodies the features of advantage enumerated as desirable in the statement of the invention and the above description, and while I have, in the present instance, shown and described an embodiment thereof which 40 will give in practice satisfactory and reliable results, it is to be understood that this embodiment is susceptible of modification in various particulars without departing from the spirit or scope of the invention or sacrificing any of its advantages. 45

Having thus described my invention,

what I claim as new and desire to secure by Letters Patent, is:

1. In combination in a circular knitting machine, a main yarn finger, a splicing yarn finger, a circle of needles having long and short butts, a set of knitting cams including the two stitch cams, one of which is pivotally supported, and the intermediate guard cam, and means to move said guard cam to cause it to be operative or inoperative with the needles having short butts. 55

2. In combination in a circular stocking knitting machine, a main yarn finger, a splicing yarn finger, a circle of needles having long and short butts, a set of knitting cams including the two stitch cams and a movably mounted guard cam, one of said 60 stitch cams being movably mounted, and pattern controlled means to effect the inward and outward movements of said guard cam. 70

3. In combination in a circular stocking knitting machine, a main yarn finger, a splicing yarn finger, a circle of needles having long and short butts, a set of knitting cams including the two stitch cams and a movably mounted guard cam, one of said 75 stitch cams being movably mounted and retained in raised position by co-operating needle butts, and pattern controlled means to effect the inward and outward movements of said guard cam. 80

4. In combination in a circular stocking knitting machine, a main yarn finger, a splicing yarn finger, a circle of needles having long and short butts, a set of knitting cams including the two stitch cams and a movably mounted guard cam, one of said 85 stitch cams being pivotally supported in proximity to one of its ends, retained in raised position by co-operating needle butts and movable to dropped position by the action of gravity and the pressure of needles 90 contacting with it, and pattern controlled means to effect the inward and outward movements of said guard cam. 95

FRANK W. ROBINSON.
